WRINGER

Walter L. Kauffman, II, Erie, Pa., assignor to
Lovell Manufacturing Company, Erie, Pa., a
corporation of Pennsylvania

Application July 11, 1932, Serial No. 621,922

10 Claims. (Cl. 68—263)

In the operation of power wringers there is a certain amount of danger of the operator becoming caught in the rolls and receiving serious injury therefrom. In order to obviate this danger means have been provided for relieving the pressure on the rolls in order to reduce the injury. In order that such a device may be useful for its purpose, it is necessary that it be so simple and obvious in its operation as to be acted upon by the operator under the conditions of fright, or panic which ordinarily prevail when the operator is caught. The present invention is designed to provide a release which, from its position and arrangement, can be instantly, conveniently and almost instinctively actuated by the operator when caught. Features and details of the invention will appear from the specification and claims.

A preferred embodiment of the invention is illustrated in the accompanying drawing as follows:

Fig. 1 shows an elevation of the wringer, partly in section.

Fig. 2 an enlarged view of one end of the top bar showing its connection with the stile.

Fig. 3 an enlarged view of the opposite end of the top bar showing the connection with the stile at that end.

Fig. 4 a section on the line 4—4 in Fig. 2.

Fig. 5 a perspective view of a latch plate. 1 marks the base of the wringer, 2 and 3 the side stiles, 4 and 5 the wringer rolls, 6 and 7 the shafts of the rolls, 8 and 9 the bearings for the shafts, 10 a spring forming the pressure means acting on the upper bearings, and 11 a screw adjusting the spring and exerting pressure from the top bar 12. The top bar 12 is of channel form with the ends preferably closed, the top bar telescoping over the top of the side stiles.

The outer wall of the stile 3 has a perforation 13 into which extends the head 14 of a screw 15. The screw extends through a perforation 16 in the end of the top bar and through a spacing collar 17. A nut 18 is arranged on the outer end of the screw and the screw is tightened on the top bar and the spacing collar 17.

Latch plates 19 are arranged at each side of the stile 2. These plates have pivot perforations 20 through which lips 21 struck up from the side walls of the stile 2 extend, thus forming a pivotal connection for the plates and also a stop for the pivotal movement. These plates are connected by a cross plate 22 so that they form an integral unit. The plates each have latch

hooks 23 which engage inwardly turned locking lips 24 which extend from the lower ends of flanges 25 on a trip lever 26. Pivot extensions 27 extend from the lips 24 into pivot perforations 28 in the side walls of the cross bar. Stop shoulders 29 are arranged on the plates 19 and engage the outer ends of the lips 24 when the lever 26 is in locked position. This engagement of the ends of the lips 24 with the shoulders 29 prevents the accidental disengagement of the hooks 10 23 from the locking lips. A spring 30 is tensioned between the top bar and the lever 26 and holds it yieldingly in locking position.

A release plate 31 has a pivot extension 32 which extends into an opening 33 in the release 15 end of the cross bar. The plate 31 extends under the end of the lever 26 and as it is rocked on the extension 32 in either direction the up-lift of one or the other of the edges of the plate 31 acting on the outer end of the lever 26 raises the 20 lever 26 carrying the ends of the lips 24 out of engagement with the shoulders 29. This same movement tilts the lips under the hooks at the point of engagement with the hooks 23 so that the hooks 23 slide off the inclined lips and release the top bar and as the top bar is released at this end of the wringer it raises and permits the unhooking of the opposite end if the raising movement is continued.

An operating bar 34 is secured to or extends 30 from the plate 31. It extends across the wringer above the top bar. It has a downward and lateral off-set 36 to expose and clear the screw 11. The opposite end of the operating bar 34 from its attachment with the plate 31 has a downwardly extending arm 37 which is provided with a perforation 38 forming a bearing on the spacing collar, or sleeve 17.

In the operation of the wringer, when this operating bar is moved either forward, or back, 40 by the operator, the pivotal movement of the bar as defined by the pivot formed by the screw 15 and the extension 32 operates the plate 31 lifting the edge of this plate and raising the release lever 26 and accomplishing the disengagement of the hooks from the latch plates and the consequent release of the top bar and with it the pressure on the spring. It will be noted that this top bar has a uniform movement throughout its length so that wherever the operator hits it, either one end or the other, it responds with a similar movement either to the front, or rear, depending on whether it is a push, or pull, and this movement actuates the release device. It will be noted also that a single operating rod 35

extends across the wringer and that this rod is directly above the wringer so that there is nothing to obstruct, or interfere with its immediate engagement in a convenient manner by the operator. It places the operating rod in a position where it is brought immediately to the notice of the operator and is, of necessity, of a form indicating to the average operator its purpose. It, therefore, makes a simple structure mechanically and one that may be readily and conveniently operated, and so positioned as to be almost instinctively reached by the operator in the panic incident to an accident.

What I claim as new is:

15. 1. In a wringer having a frame, rolls mounted in the frame, and the combination with the pressure means and frame of a pressure means for the rolls, said means comprising a spring extending across the wringer above the rolls and exerting pressure at its ends upon the rolls and devices at the center of the spring restraining the spring; a safety release device for the means comprising an operating bar extending over the top of the wringer and having movement of the bar in parallel with the axes of the rolls for actuating the release device.

20. 2. In a wringer having a frame, rolls mounted in the frame; a pressure means for the rolls, said means comprising a spring extending across the wringer above the rolls and exerting pressure at its ends upon the rolls and devices at the center of the spring restraining the spring, and a safety release device for the means comprising an operating bar pivotally mounted on an axis parallel with the axes of the rolls and extending over the top of the wringer for actuating the release device.

25. 3. In a wringer having a frame, rolls mounted in the frame, a top bar on the frame, a pressure means for the rolls acting from the top bar, and a safety release device for the means comprising a releasable securing mechanism for the top bar; the combination with said safety release device of an operating bar extending over the top of the wringer and having movement of the bar in parallel with the axis of the rolls for actuating said mechanism to release the top bar.

40. 4. In a wringer having a frame, rolls mounted in the frame, a top bar on the frame, a pressure means for the rolls acting from the top bar, and a safety release device for the means comprising a releasable securing mechanism for the top bar; the combination with a safety release of an operating bar pivotally mounted on an axis parallel to the axis of the rolls and extending over the top of the wringer for actuating the mechanism.

45. 5. In a wringer having a frame, rolls mounted in the frame, a top bar on the frame, a pres-

sure means for the rolls acting from the top bar, and a safety release device for the means comprising a releasable securing mechanism for the top bar; the combination with a safety release of an operating bar mounted on the top bar and having movement of the bar in parallel with the axes of the rolls for actuating said mechanism to release the top bar.

50. 6. In a wringer having a frame, rolls mounted in the frame, a top bar on the frame, a pressure means for the rolls acting from the top bar, and a safety release device for the means comprising a releasable securing mechanism for the top bar; the combination with a safety release of an operating bar mounted on the top bar and extending over the top of the wringer and having movement of the bar in parallel with the axes of the rolls for actuating said mechanism to release the top bar.

55. 7. In a wringer having a frame, rolls mounted in the frame, a top bar on the frame, a pressure means for the rolls acting from the top bar, and a safety release device for the means comprising a releasable securing mechanism for the top bar, the combination with a safety release of an operating bar pivotally mounted on the top bar and on an axis parallel to the axes of the rolls for actuating the mechanism to release the top bar.

60. 8. In a wringer having a frame, rolls mounted in the frame, a top bar on the frame, a pressure means for the rolls acting from the top bar, and a safety release device for the means comprising a releasable securing mechanism for the top bar; the combination with a safety release of an operating bar pivotally mounted on the top bar and on an axis below the bar and parallel to the axes of the rolls for actuating the mechanism to release the top bar.

65. 9. In a wringer having a frame, rolls mounted in the frame, a top bar on the frame, a pressure means for the rolls acting from the top bar, and a safety release device for the means comprising a latch mechanism releasably connecting the top bar with the frame; the combination with a safety release of a bar pivotally mounted on the top bar and having an axis parallel to the axis of the frame actuating said latch mechanism to release the top bar.

70. 10. In a wringer having a frame, rolls mounted in the frame, a top bar on the frame, a pressure means for the rolls acting from the top bar, and a safety release device for the means comprising a latch mounted on the frame, a release lever securing the latch, the combination with a safety release of an operating bar pivotally mounted on an axis parallel to the axis of the wringer actuating said release lever to release the latch.

WALTER L. KAUFFMAN, II. 60

CERTIFICATE OF CORRECTION.

Patent No. 2,216,198.

October 1, 1940.

WALTER L. KAUFFMAN, II.

It is hereby certified that error appears in the printed specification of the above numbered patent requiring correction as follows: Page 2, first column, lines 16 and 17, claim 1, strike out the words "the combination with the pressure means and frame of" and insert the same after the semicolon and before "a" in line 22, same claim; and that the said Letters Patent should be read with this correction therein that the same may conform to the record of the case in the Patent Office.

Signed and sealed this 27th day of January, A. D. 1942.

Henry Van Arsdale,

(Seal)

Acting Commissioner of Patents.
